CLAIM

The ornamental design for a footboard, as shown and described.

DESCRIPTION

FIG. 1 is a perspective view of a footboard according to an embodiment of the invention, the view from the opposite side being a mirror-image thereof; and,

FIG. 2 is a front elevational view of the footboard of a footboard according to an embodiment of the invention.

The dashed lines are for illustrative purposes only and form no part of the claimed invention. The back side of the footboard is not shown and forms no part of the claimed invention.
